FIRING MECHANISM FOR FIREARMS.

1,410,248.

Specification of Letters Patent. Patented Mar. 21, 1922.

Application filed August 8, 1918. Serial No. 248,980.

To all whom it may concern:

Be it known that I, GRANT HAMMOND, a citizen of the United States, residing at New Haven, in the county of New Haven and State of Connecticut, have invented a new and Improved Firing Mechanism for Firearms, of which the following is a specification.

My invention relates more especially to 10 that class of firearms in which the loading and ejection of the empty shells is automatically performed, and an object of the invention, among others, is to provide a firing mechanism so constructed that continuous firing may take place, or that single shots may be fired, that is, the parts are so arranged that the firearm may be automatic in its action or semi-automatic.

One form of device embodying my invention and in the construction and use of which the objects herein set out, as well as others, may be attained, is illustrated in the accompanying drawings, in which—

Figure 1 is a view in side elevation of a firearm embodying my invention with parts broken away to show construction.

Figure 2 is a top plan view of the frame of my improved firearm.

Figure 3 is a detail view of a portion of my improved firearm looking at the opposite side from that shown in Figure 1, parts being broken away to show construction.

Figure 4 is a detail view illustrating the operation of the controller.

Figure 5 is a similar view showing a different position of the parts.

Figure 6 is a detail view, scale enlarged, illustrating the construction of the releasing plunger.

Figure 7 is a detail view illustrating the means for locking the receiver to the frame.

Figure 8 is a detail view showing the operation of the locking bolt retainer.

Figure 9 is a detail view illustrating a slightly different arrangement of the spring for operating the two sears.

My improved mechanism has to do principally with the trigger, the hammer and connecting parts and for this reason only a small part of a firearm, sufficient for a clear understanding of my invention, is shown and described herein, reference being had to a copending application filed in my name

December 1st, 1917, Serial Number 204,921, for a description and illustration of such parts of the device as are not disclosed herein, the numeral 5 indicating the frame comprising a handle 6 and a trigger guard 7. A receiver 8 is mounted for limited sliding movement on the frame as by means of lips 9 on the lower side parts of the receiver engaging grooves 10 in opposite sides of the frame. A hammer 11 is pivotally mounted in the frame to engage a firing pin in a breech-bolt, which bolt is slidably mounted in the receiver, said bolt and firing pin being shown in Figure 3 and the operations of which will be readily understood by those skilled in the art. A trigger 12 is pivotally mounted in the frame, projecting within the trigger guard 7 and a sear actuating bar 13 is pivotally connected at one end to the trigger and projects across the handle and frame and has a notch 14 at its opposite end to receive a sear actuating finger 15 secured to a sear shaft 16.

A bar releasing plunger 17 is located in a recess in the side of the frame and is seated upon a spring 18. A controller 19 is rotatably mounted in the frame and it has a controlling lug 20 projecting from one side into a notch 21 in the actuating bar 13. The lug 20 has one edge 22 acting as a holder to retain the bar 13 in one position, an edge 23 acting as a release to permit said bar to assume another position and an edge 24 acting as a lock to secure said bar against movement. A bar releasing plunger actuator 25 receives an actuating pin 26 resting against a spring in said actuator, said pin 26 also being seated against the bar releasing plunger 17. One end of said actuator extends into a cam recess 28 in the under side of the receiver 8.

A firing sear 29 is secured to the shaft 16 and a safety sear 30 is mounted on a pivot 31 in the frame, both of said sears engaging the hammer. A breech-bolt 32 is provided with means to engage the safety sear and move it into disengaged position at about the time the breech-bolt reaches its closed position. This connection of the safety sear with the breech-bolt may be effected in different ways. As herein shown a spring pressed breech-bolt lock 33, that locks the breech-bolt from movement in the receiver,

is formed to engage the safety sear to actuate it, in this form of structure the end of said lock, in its movement to lock the breech-bolt, pressing against the end of the safety 5 sear, to disengage it from the hammer.

When the controller 19 is located with the curved locking edge 24 against the shoulder constituting the front end of the notch 21 in the bar 13, (see Figure 5) said bar is held 10 against backward movement so that the finger 15 cannot be operated to cause firing action of the firearm. When said controller is turned so that the releasing edge 23 is located opposite the deepest part of the notch 15 21 (see Figure 4) there being a space between the two parts at this time, the firearm is caused to act in a semi-automatic manner, that is, to fire one shot at each pull of the trigger. In such action the breech-bolt being 20 closed and the hammer being cocked and the trigger being pulled, the firing sear 29 will be released from the hammer, and the safety sear 30 being disengaged from the hammer by pressure of the lock 33, (the breech-bolt 25 being in its forward or closed position,) the hammer will be released, firing will take place, the receiver will be moved back a slight distance on the frame carrying with it the breech-bolt that will be unlocked 30 therefrom by operation of the lock 33 that will be actuated by this movement, and the breech-bolt will be forced backward in the receiver by the gases of explosion in the usual manner. As said receiver and bolt 35 move backwardly the cam recess 28 in the former will engage the actuator 25 and force it downwardly, and by reason of the fact that the spring 27 is stronger than the spring 18 the releasing plunger will be forced 40 downwardly, to momentarily release the bar 13 from the finger 15. This will permit the firing sear to be forced by its spring, as usual, into position to immediately reengage the hammer when it is again cocked by the 45 breech-bolt in its rearward movement, in a way that will be readily understood, and the hammer being thus held against movement firing action cannot take place until the trigger is again pulled.

When the controller is turned so that its holding edge 22 is within the notch 21, then the action of the parts just above described cannot take place for the reason that the actuating bar 13 is held in engagement with 50 the finger 15 and cannot be disengaged therefrom. This will result in full automatic action, or continuous firing of the firearm as long as the trigger is held back, until the cartridges have been expended. The 55 plunger 17 and actuator 25 constitute a sectional connector, in that they connect the receiver with the sear actuating bar 13, thus permitting the latter to be actuated by the receiver. The firing sear is disengaged from 60 the hammer at each backward movement of

the bar 13, caused by a pull on the trigger, but if the breech-bolt is not in its closed position firing will not take place for the reason that the hammer will be held by the safety sear until the breech-bolt is closed 70 and locked and the sear has been thus released. The controller may be operated by a finger piece 35 that may be retained in its different positions, as shown by full and dotted lines in Figure 3, in any desired manner.

The receiver is movably locked to the frame by a locking bolt 36 having a locking lug 37 to engage a locking recess 38 in the receiver, said recess being slightly elongated to permit movement of the receiver on the frame as clearly set out in my co-pending application herein mentioned. The bolt is movably mounted in the frame and may be operated as by means of a thumb piece 39. This locking bolt is spring pressed to engage the lug 37 with its locking recess 38, and it is prevented from being displaced by its spring by means of a breech-bolt lock actuator 40 located in the path of movement of a prong 43 on the bolt 36, said actuator being pivotally mounted in the frame with one end engaging a recess 34 in the breech-bolt lock, said lock being actuated by means of a cam 41 on the actuator. A notch 42 in the bolt 36 is arranged to receive the actuator 40 when the bolt is pressed inward and thus permit the actuator to be moved to a position for disengagement of the breech-bolt from the actuator in an effort to remove the receiver from the frame, this operation 95 of the locking bolt also unlocking the receiver from the frame to permit its removal. In assembling the parts the locking bolt is first placed in position and the actuator 40 is then secured in place in engagement with 100 the locking bolt.

In the structure of the sears as shown in Figure 9 the safety sear 44 has a spring rest 45 that is a lip projecting laterally from one side of the sear, an actuating spring 46 110 being seated upon this rest and pressing against the firing sear 29. This structure provides a single spring serving the double purpose of actuating both sears to press them into position to engage the notch in the 115 hammer.

In accordance with the provisions of the patent statutes, I have described the principles of operation of my invention, together with the device which I now consider to represent the best embodiment thereof; but I desire to have it understood that the device shown is only illustrative, and that the invention may be carried out by other means.

I claim—

1. A breech mechanism comprising movable parts including firing mechanism embodying a firing member to be released for firing action, an actuating member movably mounted to effect release of said firing 120 member.

- member, an operative connection between said members, means operated by action of one of said parts for interrupting said connection to cause single firing action, and 5 means for maintaining said connection to cause continuous automatic firing action.
2. A firing mechanism including a firing member to be released for firing action, an actuating member movably mounted to effect release of said firing member, an operative connection between said members, a frame supporting said members, a receiver movably mounted on the frame and having means to effect operation of said connection 10 to cause single automatic firing action, and means for maintaining said connection to cause continuous automatic firing action.
3. A firing mechanism including a firing member to be released for firing action, an 15 actuating member movably mounted to effect release of said firing member, an operative connection between said parts, a frame supporting said members, a receiver movably mounted on the frame and having means to effect operation of said connection 20 to cause single automatic firing action, and manually operated means for maintaining said connection to cause continuous automatic firing action.
4. A breech mechanism comprising movable parts including firing mechanism embodying a firing member to be released for firing action, an actuating member movably mounted to effect release of said firing member, an operative connection between said parts, means operated by action of one of said parts for moving said actuating member to interrupt said connection to cause 25 single automatic firing action, and means for holding said actuating member to maintain said connection to cause continuous automatic firing action.
5. A breech mechanism comprising movable parts including firing mechanism embodying a firing member to be released for firing action, an actuating member movably mounted to effect release of said firing member, an operative connection between said parts, means operated by action of one 30 of said parts for interrupting said connection to cause single automatic firing action, and manually operated means to render said interrupting means ineffective, and to maintain said connection to cause continuous 35 automatic firing action.
6. A firing mechanism including a firing member to be released for firing action, an actuating member movably mounted to effect release of said firing member, an operative connection between said members, a sectional member connected with said actuating member to operate it to cause single automatic firing action, and means to permit movement of one section of said sectional 40 member independently of the other to maintain said connection to cause continuous firing action.
7. A firing mechanism including a firing member to be released for firing action, an actuating member movably mounted to effect release of said firing member, a movably mounted member, a sectional connector between said movably mounted member and actuating member, means for holding said actuating member to cause action of a single 45 section of said connector, and means for releasing said actuating member to permit operation of the entire connector.
8. A firing mechanism including a firing member to be released for firing action, an actuating member movably mounted to effect release of said firing member, a sectional connector to operate said actuating member, one of the sections of the connector being movable independently of the other, and manually operated means to hold said actuating member in one position to cause continuous automatic firing action and to release said actuating member to permit single automatic firing action, by the operation of said connector.
9. A firing mechanism including a firing member to be released for firing action, an actuating member movably mounted to effect release of said firing member, an operative connection between said parts, a connector including one member telescoping with another to permit independent movement of one section, a member movably mounted and operatively connected with said connector, and manually operated means to retain said actuating member in one position for continuous automatic firing action and to release said actuating member to permit single automatic firing action.
10. A breech mechanism comprising movably mounted parts including firing mechanism embodying an actuating member movably mounted to effect release of a firing member, a manually operated member having means to hold said actuating member in one position for continuous automatic firing action, and means operated by action of one of said parts to effect movement of the actuating member to cause single automatic firing action.
11. A breech mechanism comprising movably mounted parts including firing mechanism embodying an actuating member movably mounted to effect release of a firing member, a manually operated member having means to hold said actuating member in one position for continuous automatic firing action, means operated by action of one of said parts to effect movement of the actuating member to cause single automatic firing action, and means to lock said actuating member against movement.
12. A firing mechanism including a firing member to be released for firing action, an

actuating member movably mounted to effect release of said firing member, an operative connection between said parts, a receiver having a cam recess, a connector composed of two sections movable one independently of the other, one of said sections projecting into said cam recess, and manually operated means to prevent movement of one section of the connector and thus cause continuous automatic firing action.

13. A firearm including a frame, a receiver removably mounted in the frame, a receiver locking bolt to lock the receiver to the frame, a breech-bolt lock actuator mounted in the frame, and connections between said actuator and locking bolt to prevent accidental removal of the latter.

14. A firing mechanism for a firearm including a member to be released for firing action, a firing sear movably mounted to engage said member, and a safety sear both

movably mounted to engage the same part of said member, and a spring interposed between and supported by said sears and exerting pressure in opposite directions to force both of the sears into engagement with said firing member.

15. A firing mechanism including a firing member to be released for firing action, an actuating member movably mounted to effect release of said firing member, a connection between said members, a controller member to permit said actuating member to have a continuous connection with a member of said connection and to permit said actuating member to have an interrupted connection with said member, and a movably mounted disengaging member engaged with said actuating member and wholly movable independently thereof.

GRANT HAMMOND.
